US0D1044234S

(12) **United States Design Patent** (10) Patent No.: **US D1,044,234 S**
(45) Date of Patent: ** Oct. 1, 2024

(54) **SHOE LAST**

(71) Applicant: **Blakely Ventures, LLC**, Atlanta, GA (US)

(72) Inventors: **Sara Blakely**, Atlanta, GA (US); **Jadideah D. Yarborough**, Atlanta, GA (US); **Sylma Colon-Otten**, Atlanta, GA (US)

(73) Assignee: **Blakely Ventures, LLC**, Atlanta, GA (US)

(**) Term: **15 Years**

(21) Appl. No.: **29/871,926**

(22) Filed: **Mar. 2, 2023**

Related U.S. Application Data

(62) Division of application No. 29/843,920, filed on Jun. 24, 2022, now Pat. No. Des. 982,304.

(51) **LOC (14) Cl.** **15-09**

(52) **U.S. Cl.**

USPC **D15/137; D2/979**

(58) **Field of Classification Search**

USPC D2/955, 959, 979; D15/136, 137

CPC A43D 3/00; A43D 3/02; A43D 3/021

(57) **CLAIM**

The ornamental design for a shoe last, as shown and described.

DESCRIPTION

FIG. 1 is a front, left-side perspective view of our new design.

FIG. 2 is a front view thereof.

FIG. 3 is a rear view thereof.

FIG. 4 is a right-side view thereof.

FIG. 5 is a left-side view thereof.

FIG. 6 is a top view thereof; and,

FIG. 7 is a bottom view thereof.

The short broken lines showing elements of the shoe last in the drawings illustrate features of the article of manufacture that form no part of the claimed design.

1 Claim, 4 Drawing Sheets
